Attorney

UNITED STATES PATENT OFFICE.

LOUIS H. DEPPE, OF BEARDSTOWN, ILLINOIS.

FILTER.

No. 903,061.

Specification of Letters Patent.

Patented Nov. 3, 1908.

Application filed September 26, 1907. Serial No. 394,647.

To all whom it may concern:

Be it known that I, LOUIS H. DEPPE, a citizen of the United States, residing at Beardstown, in the county of Cass and State 5 of Illinois, have invented certain new and useful Improvements in Filters, of which the following is a specification.

My said invention consists in certain improvements in the details of construction 10 and arrangement of parts of filters of that general character used in cistern supply systems, whereby such a filter is provided which is very efficient in operation and one wherein the first flow of water, containing 15 the washings from the roof of the building, will be discharged before passing through the filter and outside of the cistern, all as will be hereinafter more fully described and claimed.

20 Referring to the accompanying drawings which are made a part hereof and on which similar reference characters indicate similar parts, Figure 1 is a perspective view of a filter of my improved construction, and Fig. 25 2 a central vertical section through the same.

In said drawings the portions marked A represent the main casing of the filter, B a strainer-box in the top of said filter, C an automatic cut-off, D a filter-box, and E a receptacle for receiving the first flow of water.

30 The casing A is a box-like structure of suitable dimensions formed of any suitable material, preferably sheet-iron or tin, its front side being open for the greater part 35 of its length. On its top is an inlet fitting a for connection with the down-spout of the building, and at its bottom an outlet fitting a' for connection with the spout leading to the cistern. An inturned flange a^5 depends 40 from the top at its front side and serves as a deflector to deflect the incoming water toward the back of the casing.

The strainer-box B is of sheet metal 45 adapted to fit within the upper portion of the casing A where it is secured by means of supporting rivets or hooks b . It has an inclined coarse screen or strainer B' supported on its top which extends a considerable distance outside of the casing. Beneath 50 said strainer B' is another coarse strainer B^2 supported at its upper end by being connected with the back of the strainer-box and at its lower end on a cross-rod b' . The space between the cross-rod b' and the back of the 55 strainer B is filled by a finer strainer B^3

and the extreme bottom of said strainer-box is filled by another strainer B^4 .

The automatic cut-off C is a sheet metal structure of the form most clearly shown in Fig. 1, having side pieces c and being supported in the casing A on a pivot rod c' which extends through said side pieces c and the side pieces of the casing A. Said pivot rod c' is so located that the upper portion of the cut-off will normally overbalance its 60 lower portion so that its normal position will be that shown in Fig. 1, and by dotted lines in Fig. 2. An inclined deflector plate c^2 is mounted in said cut-off between its sides and behind the pivot c' . A very fine 65 mesh strainer c^3 is mounted between the end of said plate and the back edge of said cut-off being curved downwardly to form a pocket. Openings c^4 in the form of slots 70 are formed beneath said plate c^2 and screen- 75 pocket c^3 for the discharge of the water.

The filter D consists of a sheet metal casing adapted to fit within casing A and mounted with its top directly beneath the cut-off C. A horizontal screen or strainer 80 D^6 is preferably mounted across its top. It is provided with a horizontal partition D' which extends from the front toward the back of said box to an appropriate midway point and then is inclined downwardly for a 85 short distance. A strainer D^2 extends from the lower edge of said horizontal partition to the bottom of said box dividing it substantially vertically into two compartments. The bottom of said box D is open part way 90 across its area and adapted to discharge into the outlet a' of the casing. A partition D^3 extends from the bottom upwardly a short distance from the screen D^2 and the space between said partition D^3 and screen D^2 is 95 filled with filtering substance D^4 . A screen D^5 extends across the space between the partition D^3 and the front side of the box above the opening into the outlet a' .

The box E is a suitable box with an open 100 top attached to the front side of the casing A and provided with a neck E' around an outlet through its bottom for attachment with a pipe leading to a sewer, or other point of discharge.

105 In operation, the parts being in the position shown in Fig. 1 and by dotted lines in Fig. 2, the water coming through the down-spout (not shown) and the inlet a falls upon the inclined strainer or screen D' , the de- 110

5 reflector α^5 serving to deflect the water toward the back of the casing and insure that all of the discharge shall fall upon said screen, the leaves and coarse dirt which may have ac-
10 cumulated in the gutters or on the roof of the building from which the water is drained will roll off of the inclined strainer B' while the water will pass through and also through the strainer B², which will fur-
15 ther strain any particles of dirt that may have passed through the strainer B'. The water will then pass through the fine strainer B³ and through the strainer B⁴ striking the top surface of the cut-off C,
20 which, being in the position shown in Fig. 1, will discharge the water into the box E from which it will run through the waste pipe E' to the point of discharge. The water coming from the strainer-box B onto
25 the cut-off C will, however, soon fill the pocket c³ composed of the fine-mesh screen and when said pocket is filled with water the weight of the inner end of the cut-off will overbalance its outer end and cause said cut-
30 off to shift its position to the position shown in whole lines in Fig. 2, when the water will run from the deflector plate c² over the rear edge of the bottom of the cut-off, as well as through the holes c⁴, through the strainer D⁶
35 and into the filter-box D behind the screen D², through which and the filtering material D⁴ it will percolate into the compartment behind said screen D² and pass through the strainer D⁵, through the outlet α' into the pipe leading to the cistern. As soon as the water ceases to flow the pocket c³ will empty when the cut-off C will resume its normal position as shown in Fig. 1.

Having thus fully described my said in-
40 vention, what I claim as new and desire to secure by Letters Patent, is:

1. In a filter for cistern supply systems, the combination, of the casing provided with an inlet at its top and an outlet at its bottom, a strainer-box in the top of said casing provided with a top strainer projecting to the outside of the casing and with other strainers beneath through which the water must pass in flowing through said box, a piv-
45 oted automatic cut-off beneath said strainer-
50 box mounted to normally stand in an open position to conduct the water received from the strainer-box to the outside of said cas-
55 ing and formed with a pocket with a perfo-
rated bottom at its inner end which when filled with water is adapted to overbalance the outer end of said cut-off and close the same to direct the water into the casing beneath, a filter-box mounted in the lower end

of said casing beneath said cut-off divided 60 into two compartments with filtering sub-
stance between said compartments, one of said compartments being arranged to receive the water and the other compartment to dis-
charge it through the outlet to the cistern, 65 substantially as set forth.

2. A filter comprising a casing having an opening in its front side near its top, a strainer-box having a screen on its top project-
70 ing through said opening, an automatic cut-off beneath said strainer-box containing a pocket on its inner end adapted, when filled with water, to overbalance said cut-off and close the same, and a filter-box beneath said cut-off, substantially as set forth. 75

3. A filter for cistern supply systems having a casing provided with an inlet at its top and an outlet at its bottom, a screen ex-
80 tends across the top of said casing and project-
ing outside thereof, an automatic piv-
85 oted cut-off beneath said screen adapted to normally stand in position to direct the wa-
ter to the outside of said casing and formed with a pocket on its inner end which will fill with water and overbalance the outer end 85 and close said cut-off, and a filter beneath said cut-off, substantially as set forth.

4. A filter for cistern supply systems comprising a casing having an inlet, a screen beneath said inlet leading to the outside of 90 said casing, strainers beneath said screen, an automatic cut-off beneath said strainers adapted to direct the water outside of said casing when standing in open position and formed with a pocket on its inner end adapt-
95 ed to fill with water and overbalance said outer end and close said cut-off, the filter beneath said cut-off, and an outlet beneath said filter, substantially as set forth.

5. A filter for cistern supply systems comprising a casing provided with an inlet, an automatic pivoted cut-off beneath said inlet adapted to stand normally to direct the wa-
100 ter outside of said casing, formed on one side of its pivot with a pocket adapted to fill with water and overbalance the outer end of said cut-off and close it, the filter beneath said cut-off and the outlet beneath said fil-
105 ter, substantially as set forth.

In witness whereof, I have hereunto set 110 my hand and seal at Beardstown, Illinois this 10th day of September, A. D. nineteen hundred and seven.
